UNITED STATES PATENT OFFICE

ARTHUR CYRIL KNIPE, OF LONDON, ENGLAND, ASSIGNOR TO MODERN CONCRETE DEVELOPMENT COMPANY LIMITED, OF LONDON, ENGLAND

SEALING OF CONTAINERS UNDER NEGATIVE OR POSITIVE PRESSURE

Application filed February 13, 1929, Serial No. 339,709, and in Great Britain February 20, 1928.

This invention relates to containers or receptacles within which it is necessary from time to time to produce and maintain negative or positive pressure conditions.

5 More particularly the invention has reference to cylindrical containers or receptacles which require to be kept in rotation and are fitted with central doors or cover plates that are periodically opened or closed.

10 With such containers as are rotated by resting edgewise upon supporting rollers, and in which the removable cover plates are carried by independent fixtures and a hollow trunnion or trunnions are provided, the ultimate wear that may occur, i. e. relative movement between the container and the cover plates, due to the former dropping down, will interfere with, or "break" the vacuum or pressure desired.

15 The object of the invention hereinafter described is to prevent this leakage and allow the wear to be taken up and to provide a means of admitting or extracting fluids or air whilst retaining the self-aligning features 20 of the covers.

The invention consists in rotary container having removable end cover plates in which the trunnions attached to the said cover plates are so supported that relative movement may 25 take place between the trunnions and their supporting arms to take up displacements therebetween, due to wear or incorrect adjustments of the parts, thus maintaining the pressure conditions within the container.

30 The invention also consists in a rotary cement and concrete mixer having cover plates supported by trunnions carried from the frame of the machine, in which the trunnions are carried by supporting means so as to maintain the interior of the container 35 vacuum-tight and yet allow the parts to adjust themselves to take up wear or otherwise.

40 The invention will now be described with reference to the accompanying drawings which illustrate the invention as applied to a concrete mixer in which it is desired to intermittently produce a vacuum, and in which:

45 Figure 1 is a plan view partly in horizontal

section of the mounting for one of the side cover plates of a rotary mixer.

Figure 2 is a similar view of the mounting for the cover plate on the other side of the mixer, the vacuum connection being shown 55 as passing through the trunnion.

In carrying the invention into effect and referring to Figure 1, *a* is a portion of the rotary mixer where it is formed with its end opening and *b* is the cover plate adapted to 60 close such opening, a rubber or other sealing gasket *c* preferably being arranged between the two parts as indicated.

Centrally attached to the exterior of the cover plate is a solid trunnion *d* and fitted on this trunnion is a plate *e* having a packing *f* to form a tight joint between such ring and trunnion to exclude air.

The plate *e* forms one side of a hollow cup-like member the other end plate of which is 70 shown at *g* this latter member comprising an enclosing cap to close in the parts. The two plates *e* and *g* are connected together by transverse bolts *h* which pass through an annular member or distance piece *k* between the 75 two members and completing an enclosing casing. Within such casing there is arranged a self-aligning ball or roller bearing *l* which is maintained in position on the trunnion *d* between the shoulder thereon and a securing 80 nut *m*.

Such enclosing casing is supported with a certain amount of free play within an annular boss *n*, the centre part *o* of which extends inwards as an annular rib to fit between the cover plates *e* and *g* and the diameter of this annular boss *n* is substantially larger than the external diameter of the enclosing casing arranged therewithin.

The annular boss *n* is integral with or connected to a supporting arm *p* hinged at *q* upon a rigid part of the machine, whereby the cover plate and its trunnion fitting may be swung bodily outwards from the container *a*. Should there be any wear that might 95 tend to interfere with the vacuum within the container or should the parts be incorrectly adjusted, the play which is allowed between the annular boss and the inner casing permits the cover to be moved radially so that 100

it may be made to register correctly with the opening in the container, the vacuum will therefore always be preserved within the container.

5 Referring now to the other cover plate and with reference to Figure 2, the trunnion *d* in this case is hollow and its outer end is somewhat extended relatively to that in Figure 1 so that it may communicate at *q* with a 10 vacuum-duct *r* which is led transversely to a hollow hinge *s* which carries the supporting arm *p* which supports the trunnion.

The inner end of the hollow trunnion *d* is 15 preferably formed as shown in dotted lines with a pair of concentric collars *t* and *u* respectively, connected together by an intermediate flange which is bolted upon the interior of the cover plate *b*. This is constructed generally in the same way as indicated in 20 Figure 1.

By means of a spider frame *v* the trunnion tube *t* carries the mushroom shape inverted cup *w* which is wholly contained within the outer concentric wall *u* and such mushroom 25 plate fits or passes down into the annular recesses provided with the concentric collars *t* and *u* whereby the aggregate which is contained within the receiver and is in a constant state of agitation, will not be permitted to 30 choke the end of the hollow trunnion as it passes into the machine through its cover plate.

The inner end of the hollow trunnion *d* is socketed to fit a central opening or orifice 35 in the cover plate *b* and the parts are bolted up as shown.

Arranged upon the exterior of the cover plate is an enclosing casing and annular boss *o* similarly arranged to that shown in Figure 40 1 and the same letters are used for the parts as already described. The annular boss *o* in this case is fitted with a flange *x* the purpose of which is hereinafter described.

Outwardly of the enclosing casing the hollow trunnion tube passes through a stuffing box *y* and gland *z* which serves to keep the hollow trunnion air-tight and the stuffing box *y* is at its end extended outwardly at 3 to form a flange corresponding to the flange 55 *x*. To prevent any leakage of air into the container the two flanges are utilized to support an enclosing sleeve 4 of rubber, by means of rings 5 so that no air can penetrate into the space which surrounds the stuffing box and from thence into the container.

The vacuum duct *r* forms a part of a circular wall thus completely enclosing the stuffing box and gland and rubber sleeve 4 and the upper end of such wall is flanged at 7 60 which is bolted at 8 on to the annular boss, which as stated, is formed integral with or connected to the supporting arm *p*.

By the foregoing description it will be understood that the pressure conditions within the container will not be interfered with, due

to leakage of air either into or out of the container in spite of wear that may have occurred and in spite of incorrect machining and adjustment of the parts since by radial adjustment of the cover in the annular boss 70 *o* the coverplate can always be brought into proper register with the container *a*.

The container *a* is quite free to revolve on the trunnions by means of the ball bearings provided and should any wear occur, the enclosing casing formed by the parts *h*, *q* and *k* will be permitted to move eccentrically by the plate provided between it and the annular boss *o* and any incorrect movement in the lining out of the supporting bracket will be 80 corrected by the self-aligning of the ball or roller bearing.

It is not necessary to use two such cover plates as described, since one may be found sufficient and that would be the form shown 85 in Figure 2.

The system described will work just as well with sub-atmospheric pressure as with super-atmospheric pressure.

I claim:—

1. A rotary container having a removable end cover plate, a trunnion associated with said cover plate, a hinged supporting arm for said cover plate, bearing means on the said trunnion for pivotally mounting the cover plate on the supporting arm, and means interposed between the supporting arm and the trunnion bearing, permitting the cover plate to be moved in all directions in a plane at a right angle to the axis of the trunnion. 90

2. A rotary container having a removable end cover plate, a trunnion associated with said cover plate, a hinged supporting arm for said cover plate, a self aligning bearing on the said trunnion for pivotally mounting 10 the cover plate on the supporting arm, a casting to contain the said bearing and means interposed between the supporting arm and the said casting permitting the cover plate to be moved in all directions in a plane at a right angle to the axis of the trunnion.

3. A rotary container having a removable end cover plate, a trunnion associated with said cover plate, a hinged supporting arm for said cover plate, a self aligning bearing on the said trunnion for pivotally mounting the cover plate on the supporting arm, a casting to contain the said bearing, an annular boss of larger diameter than the said casing and surrounding the same, thereby permitting the cover plate to be moved in all directions in a plane at a right angle to the axis of the trunnion. 11

4. A rotary container having a removable end cover plate, a hollow trunnion associated with the said cover plate, a hinged supporting arm for the said cover plate, bearing means on said hollow trunnion for pivotally mounting the cover plate on the supporting arm and means interposed between the supporting 11

arm and the trunnion bearing, permitting the cover plate to be moved in all directions in a plane at a right angle to the axis of the trunnion.

5. A rotary container having a removable end cover plate, a hollow trunnion associated with the said cover plate, a hinged supporting arm for the said cover plate, a self aligning bearing on said trunnion for pivotally mounting the cover plate on the supporting arm, a casing to contain the said bearing and means interposed between the supporting arm and the said casing, permitting the cover plate to be moved in all directions in a plane at a right angle to the axis of the trunnion.

6. A rotary container having a removable end cover plate, a hollow trunnion associated with the said cover plate, a hinged supporting arm for the said cover plate, a self aligning bearing on said trunnion for pivotally mounting the cover plate on the supporting arm, a casing to contain the said bearing, an annular boss of larger diameter surrounding the said casing and carried by the supporting arm, the said boss permitting the casing and with it the cover plate to move in all directions in a plane at a right angle to the axis of the trunnion.

7. A rotary container having a removable end cover plate, a jointing gasket therefor, a hollow trunnion associated with said cover plate, a hinged supporting arm for said cover plate, a self aligning bearing on said trunnion for pivotally mounting the cover plate on the supporting arm, a casing to contain the said bearing, an annular boss of larger diameter surrounding the said casing and carried by the supporting arm, the said boss permitting the casing and with it the cover plate to move in all directions in a plane at a right angle to the axis of the trunnion, and means for preventing the intrusion of solid matter into the hollow trunnion.

8. A rotary container as claimed in claim 7, in which packing means are provided between the inner side of the casing and the trunnion, a stuffing box and gland on the outer end of the trunnion and a rubber enclosing sleeve between the casing and the stuffing box.

9. A rotary container having a removable end cover plate, a jointing gasket therefor, a hollow trunnion secured to said cover plate, a hinged supporting arm for said cover plate, a self aligning bearing on said trunnion for pivotally mounting the cover plate on the supporting arm, a casing to contain the said bearing, an annular boss of larger diameter surrounding the casing and carried by the supporting arm, the said boss permitting the casing and with it the cover plate to move in all directions in a plane at a right angle to the axis of the trunnion, means on the inner end of the trunnion for preventing the intrusion of solid matter into the hollow trunnion, packing means between the inner end of the casing and the trunnion, a stuffing box and gland on the outer end of the trunnion, a rubber enclosing sleeve surrounding the stuffing box and attached to the casing, a cylindrical cover surrounding the rubber sleeve and carried by the supporting arm the said cylindrical cover being provided with a vacuum duct communicating with the hollow trunnion and the hinge of the supporting arm.

10. A rotary container having a removable end cover-plate, a hollow trunnion associated with the said cover-plate, a hinged supporting arm for the said cover-plate, a vacuum duct in communication with the outer end of the hollow trunnion and extending back to the hinge of the supporting arm, bearing means on said hollow trunnion for pivotally mounting the cover-plate on the supporting arm and means interposed between the supporting arm and the trunnion bearing permitting the cover-plate to be moved in all directions in a plane at right angles to the axis of the trunnion.

In testimony whereof I have signed my name to this specification.
